UNITED STATES PATENT OFFICE

1,995,352

SELF-CENTERING END BOLT FOR
BUMPERSHerbert S. Jandus, Detroit, Mich., assignor to
General Spring Bumper Corporation, Detroit,
Mich., a corporation of Michigan

Application April 25, 1931, Serial No. 532,849

9 Claims. (Cl. 85—50)

This invention has to do with bumpers, particularly of the character embodying a pair of impact bars adapted to be supported and cushioned by a single back bar, and has for its principal object to provide a special end bolt construction of the self-centering type whereby the eyes of the respective bars will be held in proper relationship.

A further object of the invention contemplates the provision of a preferably sheet metal stamped cap adapted to substantially enclose the head of a bolt and provided with means equally spaced from the bolt shank and adapted to engage the interior wall through which the bolt is to pass. Further objects and advantages of the invention will be apparent as the description proceeds.

The invention (in a preferred form) is illustrated in the drawing and hereinafter more fully described.

On the drawing:

Figure 1 is a fragmentary plan view, partly broken away, showing a portion of a bumper constructed in accordance with the present invention.

Figure 2 is a fragmentary vertical sectional view, partly in elevation, showing the improved bolt head construction in use.

Figure 3 is a broken enlarged elevational view of a bolt to which the cap made in accordance with the present invention is secured.

Figure 4 is a fragmentary view of the bolt and head, with the protecting and centering cap shown in sections.

Referring now more particularly to the drawing, wherein the same parts are indicated throughout by the same reference characters, the bolt 1 is provided with a mushroom head 2, although it is to be understood that the essence of the present invention is applicable to any type of bolt head, and the sheet metal cap 3 completely encloses the head 2. The cap 3 is formed with a circumferential inwardly extending flange 4 from which extends a substantially cylindrical flange or skirt 5 made resilient by reason of its slots 6. The top of the cap 3 may receive any desired ornamentation and it will be clear from the foregoing that it is so constructed as to constitute a permanent part of the bolt 1.

The depending cylindrical flange 5 serves as a means for centering the shank 7 of the bolt 1 in whatever opening it may be placed, and for the purpose of illustration, the drawing depicts its use in connection with a bumper end connection. This connection consists of a pair of front or

impact bumper bars 8, having eyes 9 and 10 respectively arranged coaxially and receiving the eye 11 of the back bar 12. Juxtaposed portions of the eyes 9 and 10 are cut away or rabbeted at 13 and 14 to receive the neck 15 of the back bar 12 and to permit a certain degree of pivotal movement of the back bar eye 11 with respect to the front bar eyes 9 and 10.

In order to complete the centering of the shank 7, an element 15a constituting in effect a washer 10 engages the bottom of the eye 10 and is provided with an upstanding circumferential portion 16 formed to engage the interior wall of the eye 10 and perform the function of centering the bolt therein. A nut 17 serves to hold the parts firmly 15 in position.

With the construction just described, a bolt having a shank which is of considerably less diametral dimension than the opening through which it passes may be adequately centered there-in, without requiring special bolt construction.

I am aware that many changes may be made and numerous details of construction may be varied through a wide range without departing from the principles of this invention, and I, therefore, do not purpose limiting the patent granted hereon otherwise than necessitated by the prior art.

I claim as my invention:

1. As an article of manufacture, a self-centering end bolt for bumper bars and the like, comprising a cap engaging upper and lower portions of the bolt head, and having portions spaced from and in co-axial relation to the shank.

2. As an article of manufacture, a self-centering end bolt for bumper bars and the like, comprising a cap embracing upper and lower portions of the bolt head, and having resilient portions in co-axial relation to said shank.

3. As an article of manufacture, a self-centering end bolt for bumper bars and the like, comprising a cap embracing upper and lower portions of its head, and having a substantially cylindrical flange in co-axial relation to said shank.

4. As an article of manufacture, for centering a bolt in preformed openings of slightly varying diameters and of substantially greater transverse dimensions than the shank of the bolt, a metal cap for the bolt and of substantially mushroom shape and including a resilient shank for snugly fitting the openings.

5. As an article of manufacture, a cap for centering a shank in an opening of substantially greater transverse dimensions than the shank, said cap having a bolt head covering portion, a re-

tainning portion, and portions arranged in a substantially cylindrical form in co-axial relation to said covering portion.

6. As an article of manufacture, a bolt having 5 a head and a shank, a metallic sheath crimped onto the head so as to substantially engage the same substantially throughout, said sheath serving as an ornamental cap and said head serving to anchor the cap and also to reinforce the cap 10 against denting, and a skirt extending from the cap so as to be spaced from and substantially surround the shank, whereby to engage in an opening of substantially larger diameter than the shank to support the bolt therein.
- 15 7. As an article of manufacture, a bolt having a head and a shank, a metallic sheath crimped onto the head so as to substantially engage the same substantially throughout, said sheath serving 20 as an ornamental cap and said head serving to anchor the cap and also to reinforce the cap against denting, and a skirt extending from the cap so as to be spaced from and substantially surround the shank, whereby to engage in an opening of substantially larger diameter than the shank to support the bolt therein, said skirt being 25

resilient to compensate for variations in size of such openings.

8. As an article of manufacture, a bolt having a head and a shank, a metallic sheath crimped onto the head so as to substantially engage the same substantially throughout, said sheath serving as an ornamental cap and said head serving to anchor the cap and also to reinforce the cap against denting, and a skirt extending from the cap so as to be spaced from and substantially surround the shank, whereby to engage in an opening of substantially larger diameter than the shank to support the bolt therein, said skirt being arranged 10 inwardly of the outer periphery of the cap whereby the outer peripheral portion of the cap forms 15 an annular shoulder for engaging a body formed with such opening to limit the extent to which the bolt projects into the opening.

9. A concealing ornamental and protecting cap for a bumper end connection, comprising a 20 stamped metal member having a resilient shank adapted to fit snugly in a bumper eye, and a head having a shoulder adapted to overlie the eye, and means reinforcing the head to prevent injury thereto.

HERBERT S. JANDUS.
